UNITED STATES PATENT OFFICE.

MICHAEL FRENCH, OF LIVE OAK, CALIFORNIA.

SAFETY-ENVELOP.

1,219,635.

Specification of Letters Patent. Patented Mar. 20, 1917.

Application filed August 8, 1916. Serial No. 113,713.

To all whom it may concern:

Be it known that I, MICHAEL FRENCH, a citizen of the United States, residing at Live Oak, in the county of Sutter and State of California, have invented certain new and useful Improvements in Safety-Envelops, of which the following is a specification.

This invention relates to certain new and useful improvements in safety envelopes.

10 The primary object of the invention is the provision of an envelop adapted to be sold in the form of a blank and operatively folded around the missive and secured in position when designed for use.

15 A further object of the invention is the provision of an envelop blank having portions thereof suitably gummed for the prevention of tampering with the contents of the envelop when inclosingly arranged

20 around a missive.

With these general objects in view and others that will appear as the nature of the invention is better understood, the same consists in the novel construction, combination 25 and arrangement of parts hereinafter more fully described, illustrated in the accompanying drawings, and then claimed.

In the drawings forming a part of this application and in which like designating 30 characters refer to corresponding parts throughout the several views:—

Figure 1 is a plan view of the inner side of the present envelop blank.

Fig. 2 is a similar view thereof partially 35 folded.

Fig. 3 is a view of the outer face of one of the sealing flaps, and,

Fig. 4 is a rear view of the folded envelop formed from the blank.

40 In arranging the present device for forming a safety envelop, the same broadly consists of a blank 10 formed of suitable material such as paper and comprising a rectangular main body-portion 11 with inwardly foldable end flaps 12 and 13 and inwardly foldable side flaps 14 and 15. The said side flaps 14 and 15 will be hereinafter referred to as the top and bottom flaps respectively, being adapted for interengaging with each 45 other overlying the end flaps when the device is assembled.

The blank 10 being in the hands of the user, the missive to be sent is positioned upon the body-portion 11 and the end flap 13 50 having a transverse slot 16 therethrough is folded inwardly upon the line 17 at one end

of the body-portion while the flap 12 is inwardly folded upon the line 18 at the opposite end thereof, being provided with a tongue 19 insertible through the slot 16 with 60 the flap 13 overlying the flap 12.

The underlying flap 12 is provided with an adhesive upper portion 20 adjacent its free end and having a portion 21 thereof arranged upon the outer face of the tongue 65 19 while the outer face of the flap 13 is suitably gummed as at 22 inwardly of the slot 16 and also throughout one marginal portion of the said flap whereby the flaps 12 and 13 are adhesively secured together by the 70 portions 20 and 22 when arranged in their interlocked positions with the tongue 19 positioned through the slot 16, as best illustrated in Fig. 2 of the drawing.

The marginal portions 23 of the adhesive 75 surfaces 20 and 22 upon the flaps 12 and 13 respectively, unitedly form an adhesive surface for securing the bottom flap 15 to the side flaps when the bottom flap is folded over upon the said side flaps in contact with 80 such adhesive portions 23. The top flap 14 is arranged with a marginal adhesive portion 24 adapted to secure the top flap to the outer surfaces of the end flaps 12 and 13 when folded thereon, the said top flap having 85 a tongue 25 positionable through inner and outer slots 26 and 27 provided in the bottom flap 15. The tongue 25 is arranged with a continuation of the adhesive surface 24 of the top flap whereby the tongue is secured to the outer face of the bottom flap 15 90 between the slots 26 and 27 while the said top blank 25 has its outer face adjacent the free end of the tongue arranged with an adhesive surface 28 for securing said tongue to 95 the under face of the bottom flap 15 when positioned underlying the same extending through the slot 26. The flap 15 is provided with marginal and end adhesive surfaces 29 adapted for engaging the side flaps 100 12 and 13 outwardly of the adhesive portions 23 thereof and also to overlie and be secured to an adhesive portion 30 arranged upon the outer face of the flap 14 inwardly of the tongue 25 thereof, the said tongue 105 having an ungummed outer portion between the adhesive portions 28 and 30 for providing a plane surface between the spaced parallel edges of the slots 26 and 27 when the device is closed, as best illustrated in Fig. 4 110 of the drawings.

It will be understood that the missive (not

shown) arranged upon the base portion 11 is securely inclosed by the side and end flaps in the manner herein stated, arranging from the one piece blank a completed envelop 5 surely adhesively assembled in its closed position whereby any unauthorized tampering therewith for the purpose of gaining access to the missive will be at once apparent to the recipient thereof. It will also be noted 10 that in the event that access is had to the contents of the letter forming the present blank, it will be necessary to mutilate and spoil the envelop to such an extent that any such attempts would not only be rendered 15 apparent but of such difficulty as to render such attempts unlikely.

What I claim as new is:—

An envelop formed from a blank including a central body portion, a pair of end

flaps, one being longer than the other, the 20 longer flap adapted to overlie the shorter flap, a tongue carried by the outer end of the shorter flap, a receiving slot for the tongue formed in the longer flap, a bottom flap substantially of the form of a truncated cone, the bottom flap having a pair of parallel slots formed therein, the outer slot 25 being slightly longer than the inner slot, an upper flap adapted to underlie the lower flap in folded position, a tongue carried by the 30 upper flap adapted to pass through the slots in the bottom flap with the free end thereof covered by the bottom flap, and adhesive applied to portions of the contacting faces of the parts.

35 In testimony whereof I affix my signature.

MICHAEL FRENCH.
